UNITED STATES PATENT OFFICE.

HENRY B. SLEDGE, OF FRISCO, TEXAS.

WHIFFLETREE.

1,030,932.

Specification of Letters Patent. Patented July 2, 1912.

Application filed August 17, 1911. Serial No. 644,683.

To all whom it may concern:

Be it known that I, HENRY B. SLEDGE, a citizen of the United States, residing at Frisco, in the county of Collin and State of Texas, have invented certain new and useful Improvements in Whiffletrees, of which the following is a specification.

My invention relates to new and useful improvements in whiffle-trees. Its object is 10 to provide a whiffle-tree in which the stress of draft will be equally distributed throughout the body or beam of the whiffle-tree instead of acting almost entirely at the center of said beam as in the case of the usual devices for this purpose.

The object is more specifically to provide a whiffle-tree employing a pair of draft-rods, slightly inclined with the beam of the whiffle-tree, and having their inner ends connected 20 with a link, adapted to be secured to an implement or vehicle, the outer ends of the rods being passed through the beam extremities and provided with taps.

Finally the object of the invention is to 25 provide a device of the character described that will be simple and efficient, and comparatively easy to construct, and also one in which a lighter beam may be used than is possible in the present practice to transmit 30 a given amount of draft.

With these objects in view, my invention has relation to certain novel features of the construction, an example of which is described in the following specification and 35 illustrated in the accompanying drawing, wherein:

Figure 1 is a plan view of the complete whiffle-tree. Fig. 2 is a plan view of a slightly modified form of the device.

Referring now more particularly to the drawing, wherein like letters of reference 40 designate similar parts in both the figures, the letter A denotes the beam of the whiffle-tree, which may be made either of wood, 45 solid metal or pipe. Upon each extremity of the beam is provided a collar B, to which is rigidly attached a hook C, adapted to receive either a clevis of some sort, or the trace chains of an implement or vehicle. A 50 pair of draft rods D of equal length and size are arranged at a slight angle with the beam A with symmetrical relation to the extremities of the beam, said rods being passed through the end portions of the beam, 55 and being provided with nuts and washers

abutting against the beam extremities. The inner ends of the rods D are attached to a triangular link E, said link having one of its sides parallel with the beam A. At the juncture of the other two sides of the link 60 is provided a collar F, through which passes the shank of a swivel hook G, carrying a nut upon its extremity within the link. The hook G may be attached in any suitable manner to the vehicle or implement, in conjunction with which the whiffle-tree is used.

In the modified form of the invention shown in Fig. 2, the beam A is shown as being rectangular in cross-section, and provided with similar angle irons H at each 70 extremity, said irons being held in place by bolts or rivets, and covering the end faces of the beam, and the end portions of its forward face. The draft rods D are passed through the beam extremities in the manner already described, and are provided upon their extremities with nuts abutting against the end portions of the angle irons. The clevises J, shown in Fig. 2, are secured to the beam by bolts passing vertically through 80 the beam extremities.

In both forms of the invention, the draft is applied to the beam of the whiffle-tree at the two extremities thereof, and is transmitted to the hook G and link F through 85 the two draft rods D. The strain exerted upon the beam by the draft rods D acts longitudinally of the beam, and therefore meets with a very strong resistance, so that the beam will not readily be broken. By 90 thus subjecting the beam to a longitudinal strain, and securing the full advantage of the strength of the beam, it is made possible to use lighter material or to use weaker and less expensive material.

It is to be understood that any form of 95 clevis may be used in conjunction with the above described invention, and that the specific form of connection between the link E and the vehicle or implement may be 100 varied in a number of ways. The invention is therefore presented as including all such changes and modifications as are covered by the following claim.

What I claim is:

In a device of the character described, the combination with a beam, of a pair of rods symmetrical with the beam extremities, and passing through said extremities at a slight angle with the beam, means rigid upon said 110

rods abutting against the beam extremities, a triangular link, with which the adjacent extremities of said rods are connected, one side of said link being parallel with the beam, a sleeve rigid with said link at the juncture of its other two sides, and a swivel-hook mounted in said sleeve.

In testimony whereof I have signed my name to this specification in the presence of two subscribing witnesses.

HENRY B. SLEDGE.
